UNITED STATES PATENT OFFICE

116,158

DESIGN FOR A LADY'S HANDBAG OR SIMILAR ARTICLE

Benjamin Robert Brody, New York, N. Y.

Application July 1, 1939, Serial No. 85,809

Term of patent 3½ years

To all whom it may concern:

Be it known that I, Benjamin Robert Brody, a citizen of the United States, residing at New York, in the county of Bronx and State of New York, have invented a new, original, and ornamental Design for a Lady's Handbag or Similar Article, of which the following is a specification, reference being had to the accompanying drawing, constituting a part thereof, in which:

Fig. 1 is a plan view of a lady's handbag showing my new design.

Fig. 2 is an end elevational view of Fig. 1 as seen from the left hand side thereof.

Fig. 3 is a bottom view of the handbag shown in Fig. 1.

Fig. 4 is a plan view taken similarly to Fig. 1 in which the closure members of the handbag are in an open position thereof thereby exposing to view a portion of the inside of the handbag.

Fig. 5 is a front elevational view showing the configuration taken by the handbag of Fig. 1 when the same is suspended by means of the handle thereof.

Fig. 6 is an end elevational view of Fig. 5 as seen from the right hand side thereof.

I claim:

The ornamental design for a lady's handbag or similar article, as shown.

BENJAMIN ROBERT BRODY.
